REELING APPARATUS

Chester A. Mathey, Tulsa, Okla.

Application October 2, 1937, Serial No. 166,931

5 Claims. (Cl. 254—173)

This invention relates to a reeling apparatus and more particularly to an apparatus of that character adapted to lower and raise instruments and/or explosive charges into and from a well hole, for example, for lowering explosive charges into an oil well for the purpose of enlarging the oil pocket for the reception of oil therein.

In raising and lowering such explosive charges into oil well holes, care must be exercised during the descent or ascent of such charges in order to avoid damage to the well and loss of equipment.

In present day oil producing operations, it has been found advantageous to store oil in the ground at the oil well location for the reason that there is less evaporation of the oil and less expense involved than in storing the oil above ground in open ponds or covered tanks. It is desirable, however, to check the conditions of the well products as they are stored. For example, frequent runs are desirable to determine the density of the oil in the various strata thereof, the temperature and pressure of the oil and other conditions within the well.

It is, therefore, the principal object of the present invention to provide the reeling apparatus with controlling mechanisms for maintaining a substantially constant and/or balanced descent and ascent velocity of an instrument when it is descending into the well hole and being drawn therefrom.

Other objects of the present invention are to provide a hydraulic pump which is connected with the reeling apparatus and operated thereby during rotation of the reel for controlling speed of rotation of the reeling apparatus; to provide motive power for rotating the reel to rewind a line on which the well instrument is mounted; to provide a transmission on the motive power mechanism which is connected with and operates the pump whereby ascent velocity of the instrument in the well is controlled; to provide the motor with a controlled connection to the reel whereby the reel is rotated at a constant speed relative to actuation of the hydraulic mechanism; to provide a circulation line for the hydraulic mechanism which is affected by the winding and unwinding of the line from the reeling apparatus for controlling pressure in the hydraulic mechanism; to provide a pump controlling emergency valve mechanism in the line; to provide a measure meter connected with and operated by the line as it is being wound and unwound from the reeling apparatus; to provide

braking mechanisms for controlling rotation of the reel in emergencies; to provide improved clutch mechanisms interconnecting the reeling apparatus, hydraulic mechanism, and motive power mechanism; and to provide a commutator on the reeling mechanism whereby an instrument on the line may be energized for indicating well conditions in the well on instruments at the top of the well.

In accomplishing these and other objects of the invention, I have provided improved details of structure, the preferred form of which is illustrated in the accompanying drawings wherein:

Fig. 1 is a plan view of a reeling apparatus embodying the features of the present invention and shown mounted in a trailer.

Fig. 2 is a side elevational view of the reeling apparatus, the trailer body being shown in section to illustrate mounting of the reeling apparatus therein.

Fig. 3 is an end elevational view showing the reel in section and illustrating the commutator at one end of the reel shaft, and the reel shaft sprocket and clutch members at the other end of the shaft.

Fig. 4 is a fragmentary side elevational view in the direction opposite that of Fig. 2, particularly illustrating the hydraulic pump and surge and fluid pressure medium reservoir tanks.

Fig. 5 is a detail horizontal section through the transmission, the sprocket and shafts thereof being shown in plan.

Fig. 6 is an elevational view of the circulation line valve and governor therefor, parts of the valve being broken away to better illustrate its construction.

Fig. 7 is a fragmentary plan view of the sprocket end of the reel, illustrating the connections between the reel shaft clutch members and the hydraulic pump drive shaft clutch members.

Fig. 8 is a vertical section through the emergency braking apparatus.

Fig. 9 is a detail perspective view of the measure meter mounting.

Referring more in detail to the drawings: The invention generally consists of a movable support 1 mounting a reeling mechanism 2 having a commutator 3 at one end thereof and a reel shaft clutch member 4 at the other end thereof. A line 5 is wound upon the reel and is extended through a measure meter 6, the measure meter being carried from the support by the mounting 1. Descent velocity of an instrument (not shown) on the line is manually controlled

by the braking element 8. An hydraulic mechanism 9 is also mounted on the support and adapted to be connected with the reeling mechanism 2 for controlling rotation thereof to maintain the descent velocity of the instrument on the line 5 uniformly constant. A motive power unit 10 is also mounted on the support, which has a transmission including a housing 11 and a power takeoff 12 interconnected with the hydraulic mechanism and reeling apparatus, respectively, for controlling ascent velocity of the instrument on the line as it is being withdrawn from the well in response to rotation of the reeling mechanism by the motive power unit. A circulation line 13 is connected with the hydraulic mechanism 9, circulation in the line being controlled by a valve 14 responsive to actuation of a governor, which is operated by a line engaging pulley 15, the circulation being further controlled by a three-way throttle valve 16 in the line 13 and connected with a by-pass line 16', which bypasses fluid pressure medium around the governor and is so arranged with the valve that back pressure can be held on the line from the pump and can be released either to the governor actuated valve or the by-pass line 16'. Fluctuations in pressure in the lines are recorded by the gauge 17, which indicates ascent and descent speeds of the instrument in the well and other well conditions.

More particularly, the support 1 preferably consists of a trailer including a box-like body 18 carried on an axle 19 having wheels 20, the body being provided at its forward end with a suitable draft element 21 connectable with a tractor, truck or other similar draft vehicle. It is apparent that, while a trailer is shown as the movable support for the reeling apparatus, the reeling apparatus may conveniently be mounted on a truck, or in the back of an automobile, and driven by the motive power of such vehicle.

The reeling mechanism 2, Fig. 2, is preferably mounted in the trailer body on bearing supports 22, which are provided with laterally extending flanges fixed to the floor of the body by fastening devices 23. The bearing supports are provided at their upper ends with bearings 24 having lateral flanges connected to the bearing supports by suitable fastening devices 25. One of the bearing members 24 is provided with an end cap member 26 to form a dust seal to prevent wear of the bearing and the reel shaft 27, which has its outer ends mounted in the bearings. A reel 28 is mounted on the shaft between the bearings and is keyed to the shaft in a suitable manner, as shown at 29, for rotating with the shaft when power is applied to the reel or shaft and particularly for rotating with the shaft in response to unwinding of the line 5 from the reel when an instrument applied to the line is placed over and allowed to descend into a well hole.

The reel 28 is provided at one end with the commutator 3 which preferably consists of a pair of conductor rings 30 mounted on an insulated hub portion 31 of the reel. The rings 30 have electrical connection with conductors 32 which are suitably mounted within the line 5 in such a manner that instruments on the line may be electrically connected therewith and with the commutator. Brushes 33, Fig. 1, are mounted on the bearings 24 adjacent the commutator by brush supports 34, which are provided with terminals in a suitable manner for connection

with indicators or the like, not shown, to indicate the well conditions.

The line 5 is preferably extended through the measure meter 6, as shown in Fig. 2, which measure meter consists of a housing having pairs of aligned wheels 35 rotatably journaled on the housing by pins or the like 36, certain of the wheels being preferably interconnected by a gear 36, which actuates a counter 37, Fig. 1, and others of the wheels being provided with a tensioning device 38 for effecting positive engagement of the measure meter with the line, whereby an accurate measurement of the length of the line payed into the well is effected.

The measure meter 6 is mounted on the trailer 15 by means of the meter mounting 7, previously mentioned, as shown in Figs. 1 and 9, the trailer being provided with a socket 39 for swivelly receiving a pin 40 forming a part of and depending from a bar 41 which has pivotally mounted thereon a bar extension 42 provided with an upwardly projecting socket 43, the socket 43 preferably being formed of pipe to receive a suitable pin or other fastening member on the measure meter. With this arrangement the measure meter is swivelly mounted for horizontal movement relative to the trailer in such a manner that its position may correspond to the position of the line as it plays from the reel. It is also apparent that the pivotal connection 44 of the rod extension 42 with the rod 41 adapts the measure meter for pivotal vertical movement relative to the trailer in such a manner that vibrations, jolts, and the like, incidental to operation of the reeling apparatus, are taken up so that the measure meter is at all times maintained in operable condition. A weight 45 is suitably connected, as shown at 46, with the rod extension 42 for creating a constant tension of the measure meter on the line to enhance accuracy of the measurements of the line as it is being payed to and from the reel.

With the construction thus far described, it is apparent that an instrument on the line may be lowered into the well, that the length of the line payed into the well may be measured, and that conditions in the well may be indicated through the line at the top of the well simultaneously with measurements of the line to register the position of the noted well conditions.

The braking element 8, shown in Fig. 8, is for manually controlling descent velocity of the instrument into the well, the braking element consisting of a brake band 47, which is frictionally mounted on the end member 48 of the reel, the brake band being provided with laterally extending ears 49 having apertures therein for receiving brake rods 50 which have their opposite ends pivotally mounted in an actuating member 51 in turn fixed, as shown at 52, to a conventional hand lever 53 provided with a ratchet mechanism 55. The brake lever is mounted on a bracket 56 suitably secured to the floor of the trailer in such a manner that movement of the hand brake lever away from the reeling member pivots the brake rods and draws the brake band ends thereof toward each other to increase frictional contact of the brake band with the reeling member to impede rotation of the reeling member and thus reduce descent velocity of the instrument into the well.

While the braking element is adequate for impeding and stopping descent of the instrument into the well, I have found it desirable to positively control descent of the instrument and

5 maintain its descent velocity uniformly constant and in balance with the speed of rotation of the reel, for the reason that when delicate instruments are being lowered into the well, variations 10 in descent velocity of such instruments or charges are quite likely to damage the instrument or effect premature explosion of the charge. I, therefore, provide the hydraulic mechanism 9 for selectively controlling rotation of the reeling 15 member and consequently maintaining the descent of the instrument or charge constant.

10 The hydraulic mechanism 9 consists of an hydraulic pump of conventional design, the pump, however, being provided with a driving shaft 15 57 extending outwardly from the pump to a location spaced outwardly from the end member 58 of the reeling member. The shaft 57 is provided adjacent its outer end with a gear wheel 59 having teeth thereon, which are engageable 20 with the teeth 60 provided on the periphery of the reel end member 58 in such a manner that, as the reel is rotated in response to descent of the instrument into the well under force of gravity, such rotation is transmitted to the gear 25 59 and shaft 57 for actuating the fluid pump or hydraulic mechanism 9 and setting up circulation of fluid pressure medium in the circulation line 13 or by-pass line 16' depending upon the position of the valve 16, which affects 30 actuation of the pump 9 and therefore rotation of the reel to maintain the rotation of the reel at the speed of the pump or in balance therewith. The instrument on the line is therefore maintained at a uniform descent velocity depending 35 upon the speed of the pump through circulation of the pressure medium through the respective lines.

40 In order to ascertain well conditions throughout descent of the instrument in the well, the gauge 17 is provided, which is mounted on a surge tank 61, as shown in Fig. 4, the surge tank being connected by a tube 62 and T member 63 to the circulation line 13. It is apparent that fluctuations in descent velocity of the instrument 45 affects rotation of the reel, which in turn affects actuation of the pump, which fluctuations in circulation are recorded by the gauge in such a manner that an operator observing the gauge is able to ascertain the well conditions.

50 The throttle valve 16 is also used to control descent velocity of the instrument into the well, the throttle valve preferably being of conventional design and being mounted at a juncture of the circulation line 13, and by-pass line 16'. 55 The throttle valve is for increasing or decreasing resistance to circulation of fluid pressure medium in the circulation and by-pass lines in such a manner that speed of actuation of the hydraulic pump is accordingly increased or decreased.

60 An oil reservoir 66 is also mounted in the circulation line in a convenient position for maintaining a head of fluid pressure medium for the hydraulic pump through a connection 67.

65 I have found it desirable to further control circulation of fluid pressure medium throughout the circulation line, and to this end, I have provided the governor 14 in the circulation line 13, the governor being particularly illustrated in 70 Fig. 6. A valve body 68 is mounted in the circulation line 13, which has an inlet compartment 69 communicating with an outlet compartment 70 thereof through a valve opening 71, the valve opening 71 being controlled as to size by 75 the valve 72 which is fixed to a preferably ver-

tically extending valve stem 73. The valve stem 73 extends upwardly out of the bored flange 74 of the valve body 68 and into the bored flange 75 of the governor body. The flanges 74 and 75 are suitably fixed in sealing relation by the 5 fastening devices 76 and the valve stem 73 is connected with the governor arms 77 in the usual manner in order that, as the governor stem 78 is rotated through rotation of the beveled gear 79 by the connected gear 80, the governor 10 arms 77 are rotated and lifted by centrifugal force to also lift the valve stem 73 and the valve 72 to close the valve opening 71 for increasing 15 resistance to circulation of fluid pressure medium in the circulation line for slowing down actuation of the hydraulic pump to consequently reduce descent velocity of the instrument in the well and thus maintain such velocity at a constant speed.

20 The governor is actuated by a sprocket 81 which is fixed to the gear 80 in a suitable manner exteriorly of the governor body, the sprocket 81 being turned preferably by a chain 82 which passes over a sprocket 83, as particularly shown in Fig. 1. The sprocket 83 is mounted at one 25 end of a driven shaft 84 which has its ends rotatably mounted in bearings 85 preferably secured to the floor of the trailer. Rotation of the shaft 84 is effected by a sheave 87 or the like, which is preferably keyed to the shaft 84, 30 but which is adapted to slide laterally relative to the shaft in such a manner as to receive the line 5 in the peripheral groove 88 thereof and follow the line in its relative positions on the reel as the line is being wound or unwound from 35 the reel, it being apparent that, as the line is unwound relative to the reel, its frictional contact with the sheave 87 rotates the same and consequently the shaft 84 to actuate the governor 40 for affecting circulation in the line in proportion to speed of descent of the instrument into the well to thus create a balance between actuation of the pump, rotation of the reel and descent of the instrument into the well.

45 A shaft 99 is also mounted on the trailer by the bearings 90, which is provided with a sheave 91 rotatably mounted on the shaft and alignable with the sheave 87 in such a manner that the line 5 may be threaded under the sheave 87 and over the sheave 91 for effecting more positive 50 engagement of the line with the sheave 87 and consequently causing positive actuation of the governor valve 14 in response to movement of the line.

55 With the construction thus far described, it is apparent that I have provided a reeling apparatus which is adapted to lower an instrument into a well, the descent velocity of such instrument in the well being balanced with rotation of the reel and actuation of the hydraulic pump 60 in such a manner that a constant velocity of the instrument is maintained relative to the reel so that line entanglements are prevented and efficient operation of the reeling apparatus is effected.

65 It is necessary to provide for rewinding the line on the reel to withdraw the instrument from the well and to this end, I provide the motor 10, the motor proper being of conventional design and being provided with a drive shaft 92, which is engaged through a suitable coupling 93 with the driven shaft 94 of the transmission 11. The shaft 94 of the transmission is rotatably journaled in a bearing 95, the bearing 95 being mounted in an opening 96 at one side of the 75

housing 11, which encloses the transmission elements. The opposite side of the transmission housing is closed by a sprocket 97, which is fixed thereto by suitable fastening devices 98 and which 5 is provided at its periphery with sprocket teeth 99. The sprocket 97 is provided at its center with an opening 100 for receiving a bearing 101 in which a shaft 102 is rotatably mounted. The opening 100 is reduced at the inner face of the 10 sprocket to form a seat 103 for the hub 104 of a sun gear 105, the sun gear being keyed, as shown at 106, to a reduced portion 107 of the shaft 102 adjacent the inner end. The sun gear 105 is further provided with a bearing 108 engaged 15 about the shaft 94 for rotatably mounting the sun gear 105 on the shaft 94, yet fixing the sun gear 105 to the reduced portion 107 of the shaft 102 thereby supporting the inner ends of both shafts. A sun gear 109 is keyed, as shown at 20 110, on the shaft 94 adjacent the opening 96 in the transmission housing 11. Aligned openings 112 and 113 are provided in the transmission housing and sprocket, respectively, for receiving the ends of a shaft 114 on which is mounted the 25 planetary gear 115, the planetary gear having a set of gear teeth 116 which are engageable with the gear teeth of the sun gear 109, a set of gear teeth 117 also being provided on the planetary gear 115 which are engageable with the gear teeth of the sun gear 105. A planetary gear 118, similar to the planetary gear 115, is mounted in the transmission housing 11 on a shaft 119 mounted in aligned openings 120 and 121 in the transmission housing and sprocket 97, respectively, which planetary gear 118 has teeth 122 engageable with the teeth of the sun gear 109 and teeth 123 engageable with the teeth of the sun gear 105.

A sprocket wheel 124 is keyed adjacent the 40 outer end of the shaft 102, which is provided with teeth 125, the extreme outer end of the shaft 102 being mounted in a suitable bearing 126, which is secured to the trailer floor by fastening devices 127.

A chain 128 is engaged about the sprocket 124 and extends toward the reeling member for engagement about the toothed sprocket 129 of a floating clutch member 130 mounted on the outer end 131 of the reel shaft 27, as shown in Figs. 2 45 and 3, it being apparent that, as the motor 10 is actuated and the sprocket 124 rotated, loose rotation of the sprocket 129 on the reel shaft is also effected.

A chain 132 is also mounted on the sprocket 97 55 of the transmission which extends over and about a sprocket 133 which is loosely mounted on the outer end of the hydraulic pump driving shaft 57, the extreme outer end of such shaft being mounted in a suitable bearing 134 which is preferably fixed to the floor of the trailer by suitable fastening devices 135. It is apparent that, as the 60 transmission housing as a whole is rotated in response to rotation of the motor drive shaft, the sprocket 133, due to its loose mounting on the shaft 57, is also rotated on the shaft 57, neither the sprocket 124 nor the transmission gear wheel transmitting any power to the pump shaft 57 or the reel shaft 27 with the construction thus far described.

There is a tendency for the transmission housing 11 and the sprocket 124 to rotate in response 70 to rotation of the shaft 94 of the motor 10 when the motor is actuated. If resistance is applied to the transmission housing 11 and the sprocket 124 remains free, the tendency is for the transmission 75 housing to cease rotation and yet the sprocket

continues to rotate. When resistance is applied to the sprocket 124, the tendency is for the sprocket to cease rotation while the transmission housing continues its rotation. Thus a selective driving connection of the motor with the reel 5 and pump is effected by selectively taking power from the transmission or sprocket respectively.

As above pointed out, the transmission is connected through the chain 132 with the pump shaft sprocket 133. The pump shaft sprocket is 10 provided on its inner face with clutch teeth 136, Fig. 1, which are engageable with clutch teeth 137 of a clutch member 138 which is fixed to the pump shaft gear 59. A clutch lever 139 is loosely mounted on the clutch member 138 and is fixed to a pump clutch shaft 140 which has its ends 15 mounted in bearings 141 and 142 respectively fixed in a suitable manner to the floor of the trailer. The end 143 of the pump clutch shaft is pivotally mounted on a bell-crank 144 which is pivotally mounted, as shown at 145, to the floor of the trailer and which has an angularly extending arm on which is pivotally mounted an angularly extending rod 146. The rod 146 is pivotally connected with a hand lever 147 which is placed conveniently relative to the measure meter and gauge 17 in such a manner that an operator of the reeling apparatus may stand in one position and observe the reading of the measure meter, the fluctuations of the gauge, and also actuate the pump clutch shaft hand lever. As the clutch lever 147 is moved in one direction, for example, to the right, as shown in Fig. 1, such motion is transmitted to the gear wheel 59 to effect its engagement with the gear wheel 60 of the reeling member. This operation is for the purpose of connecting the reeling member with the hydraulic pump shaft for controlling descent velocity of an instrument on the line. Upon reverse motion or shifting of the clutch lever 147, the gear wheel 59 is moved on the shaft 57 away from the gear wheel 60 to effect interengagement of the clutch members 136 and 137 for connecting the hydraulic pump with the transmission to control ascent velocity of the instrument on the line when the reel is rotated to wind the line thereon in response to actuation of the motor 10.

Such interengagement of the hydraulic pump clutch member with the transmission clutch member is particularly illustrated in Fig. 7 which also illustrates the clutch member 4 on the reel shaft 27.

As above pointed out, the clutch member 130 is loosely mounted on the outer end 131 of the reel shaft 27 and is provided with clutch teeth 148 which are interengageable with clutch teeth 149 on a clutch member 150 which is suitably fixed to the outer end of the reel shaft 27. A clutch yoke 151 is loosely mounted on the clutch member 150, the yoke being fixed to a shaft 152 which has its ends mounted in bearings 153 and 154 fixed on the floor of the trailer in spaced relation to the bearings 141 and 142 of the pump shaft clutch lever mechanism. The shaft 152 has its end opposite the clutch member pivotally mounted on one arm of a bell-crank 155, which is suitably fixed, as shown at 156, to the trailer floor. The other arm of the bell-crank has pivotally mounted thereon a link 157 to which is secured a hand lever 158 adjacent the pump clutch lever 147 in such a manner that a single operator may conveniently actuate both levers for selectively connecting the respective clutches thereof, the reel shaft 27 with the motor sprocket 124, and the pump shaft with the transmission 11 respectively in such a manner that, as the 75

motor 10 is being actuated to rotate the reel in a direction suitable for winding the line thereon, the transmission is engaged with the pump shaft for creating a balance between the motor, pump and reel so that the ascent velocity of an instrument, as it is being drawn out of the well, is in proportion to the speed of the motor 10 and its withdrawal is therefore smooth and without jerks so that hazard to the instrument on the line is precluded.

A hand lever 159 is also located on the trailer floor adjacent the hand levers 147 and 158, which is connected by a rod 160 with one arm of a bell-crank 161 pivotally mounted relative to the trailer, as shown at 162. The other arm of the bell-crank is provided with a connecting rod 163, which is pivotally secured to a lever 164 on the motor clutch shaft 165 for effecting drive of the motor drive shaft 92 in response to the conventional engagement of gears in the gear box 166 of the motor in response to actuation of the motor hand lever 159.

The operation of a reeling apparatus constructed as described is as follows:

Assuming the trailer or other support for carrying the reeling apparatus to be positioned adjacent a well hole, the line or cable 5 is threaded under the sheave 87 and in the groove 88 thereof and over the grooved sheave 91. The line is further extended and threaded through the measure meter 6, as shown in Fig. 2, and the end of the line is provided with an instrument adapted to be electrically energized through its connection with the line and the commutator 31 in such a manner that well conditions may be recorded on suitable gauges at the top of the well. The instrument, or an explosive charge, as the case may be, is attached to the line and placed over the well hole.

The hand lever 158 is then moved to disengage the reel shaft clutch members and the hand lever 147 is moved to effect engagement of the pump shaft gear wheel 59 with the reel gear wheel 58. The brake lever 53 is then moved to release the brake band from the reel and the instrument is lowered into the well by gravitation and consequently rotates the reel as the line is unwound therefrom. Rotation of the reel is controlled by the hydraulic pump 9 since the shaft of the pump is rotated in response to rotation of the reel through the gear wheel 59.

During such actuation of the pump, fluid pressure medium is circulated through the line 13 or by-pass line 16' depending upon the position of the three-way throttle valve 16, and fluctuations are recorded on the gauge 17 in such a manner that the operator of the apparatus may ascertain descent conditions, for example, velocity of descent of the instrument into the well. Under one set of conditions, for example, circulation is further controlled by the throttle valve 16 so that circulation may be increased or decreased through the pump for further affecting descent velocity of the instrument. As the line 5 is unwound and as it travels over the sheaves 87 and 91, the shaft 84 is rotated to actuate the governor valve 14 in proportion to speed of rotation of the shaft, or descent of the instrument, the governor valve opening or closing depending upon the speed of descent of the instrument and therefore further controlling circulation of fluid pressure medium in the hydraulic pump circulation line.

It is apparent that the sheaves are adapted to reciprocate laterally on their shafts in corre-

spondence to the relative positions of the line on the reel and that the measure meter is adapted to swing both horizontally and vertically in response to the position of the line in such a manner that accurate recordings are obtained from the counter 37 of the measure meter, the line always being held taut relative to the measure meter by the weight on the measure meter mounting.

When the instrument or charge has reached the bottom of the well and the recordings have been obtained relative to conditions of the well, the lever 158 is moved to effect engagement of the reel shaft clutch members to effect a driving connection between the motor 10 and the reel shaft. The clutch lever 147 is also moved to effect disengagement of the pump shaft gear 59 from the reel gear 60 and engagement of the pump shaft clutch members to thus connect the pump with the motor through the transmission sprocket. The motor 10 is then energized and the hand lever 159 therefor is moved to effect clutching engagement of the motor with the drive shaft 92 and the transmission drive shaft 94 for rotating the shafts and driving the sprocket 124 to rotate the reel. As the reel is rotated, the line is wound thereon in reverse manner to that above described and the hydraulic pump, which is connected to the motor through the chain and sprocket connections of the transmission acts on the motor and indirectly on the reel to create a balance between the speed of the motor and the ascent of the instrument.

The mentioned balance is effected by reason of the tendency of both the transmission housing 11 and sprocket 124 to rotate together in response to actuation of the motor. It is apparent, however, that since the transmission is connected with the hydraulic pump shaft, a resistance is set up in opposition to rotation of the transmission of an intensity depending upon fluid displacement of the hydraulic pump, which in turn is governed, in part, by the speed in winding of the line on the reel, or in other words, speed of ascent of the instrument in the well. Resistance to rotation of the transmission causes a slip in the sun and planetary gears of the transmission relative to the sprocket shaft 102, which resists rotation of the sprocket 124 in proportion to the amount of slip or resistance in and to rotation of the transmission. The reel is, therefore, rotated through the sprocket 124 at a speed proportionate to resistance of the hydraulic pump. Since the hydraulic pump is actuated at a speed proportionate to the speed of the ascent of the instrument, a balance between the instrument and reeling apparatus is thus effected.

The result of this balance is that the ascent of the instrument as it is being withdrawn from the well is uniform and unbroken and fluctuations in the recordings are uniform and easily ascertainable in such a manner that the well conditions and the condition of the instrument or charges are protected.

The principal advantages in an apparatus constructed in accordance with my invention are that accurate recordings may be obtained of well conditions. Danger of premature explosions of explosive charges is eliminated. Ascent and descent velocities of instruments or charges in the well are balanced with the motive power effecting such movements, and a smoothly operating machine is provided which is efficient in such operation.

What I claim and desire to secure by Letters Patent is:

1. In a reeling apparatus, a support, a reel rotatably mounted on the support, a line wound on the reel adapted to receive an instrument and raise and lower same relative to a well hole, a 5 hydraulic pump mounted on said support, means operatively connected with the pump and engageable with the reel adapted to actuate said pump in response to rotation of said reel, a fluid pressure medium circulation line connected with said 10 pump, a valve mounted in said circulation line, a governor operatively connected with and controlling actuation of said valve, means on the support adapted to receive the line as it is payed from the reel, means operatively engaged with 15 said line receiving means operatively engaged with the governor for actuating same responsive to movement of said line to affect circulation of hydraulic pressure medium through the valve and pump for controlling velocity of rotation of said 20 reel, a throttle valve mounted in the circulation line cooperative with the first named valve in affecting circulation through the pump, and a by-pass line connected with the circulation line and by-passing the governor, said line being controllable by the throttle valve for creating back-pressure on the pump.
2. In an apparatus of the character described, a reel having a line wound thereon and adapted to be payed therefrom, a circulating duct, a hydraulic pump having inlet and outlet connections with the circulating duct for circulating a fluid medium through the duct, a driving connection between the reel and pump, a throttle valve in said circulating duct controlling circulation of 35 the fluid medium by said pump to regulate speed of the pump and exert a braking influence on said reel, a pulley having driving contact with the line payed from said reel, a centrifugal governor having driven connection with the pulley, 40 means connecting the centrifugal governor with the throttle valve to effect control of the circulated medium responsive to pay of the line from the reel, a by-pass duct connected with the circulating duct in by-passing relation with the 45 throttle valve for circulating fluid medium around the throttle valve, and a manually actuated valve connected in said ducts for selectively controlling flow of the circulated medium through the throttle valve and said by-pass duct.
3. In an apparatus of the character described, 50 a reel for winding a line thereon, a motor, a driv-

ing shaft connected with the motor, a power shaft, a driving connection between the power shaft and said reel, sun gears on the respective shafts, planet gears interconnecting the sun gears, means mounting the planet gears for 5 planetation about the sun gears, hydraulic means controlling planetation of the planet gears, means for connecting the planet gears with said hydraulic means, regulating means for controlling said hydraulic means, means having driven contact with the line for actuating the regulating means, means for connecting the hydraulic means with the reel, and means for selectively rendering said connecting means effective.

4. In an apparatus of the character described, 15 a reel for winding a line thereon, a motor, a driving connection between the motor and the reel, a hydraulic pump, a differential in said driving connection, means connecting the differential with the hydraulic pump, a circulating duct connected with the hydraulic pump, a throttle connected with said circulating duct for controlling circulation of fluid medium by said pump, means actuated responsive to pay of the line onto the reel for actuating the throttle to effect control of 20 said differential responsive to pay of the line onto the reel, a by-pass connected with the circulating duct on the respective sides of the throttle, and means for selectively controlling said by-pass.

5. In an apparatus of the character described, 30 a reel for winding a line thereon, a motor, a driving connection between the motor and the reel, a hydraulic pump, a differential in said driving connection, means connecting the differential with the hydraulic pump, a circulating duct connected with the hydraulic pump, a throttle connected with said circulating duct for controlling circulation of fluid medium by said pump, a centrifugal governor connected with the throttle, means for actuating the centrifugal governor responsive to pay of the line onto the reel to control said fluid medium circulated by the hydraulic pump for effecting operation of the speed of the differential responsive to pay of the line onto the reel, a by-pass connected with the circulating 45 duct on the respective sides of the throttle, and valve means selectively rendering the by-pass effective for controlling flow of the circulated medium and effecting variation in speed of the differential independently of the throttle valve. 50

CHESTER A. MATHEY.
